US0D1019278S

(12) **United States Design Patent** (10) Patent No.: **US D1,019,278 S**
Wood et al. (45) Date of Patent: ** *Mar. 26, 2024

(54) **CUP**

(71) Applicant: **Bockatech Ltd.**, Huntingdon (GB)

(72) Inventors: **Lewis Wood**, Huntingdon (GB);
Martin Blacher, Huntingdon (GB)

(73) Assignee: **Bockatech Ltd.**, Huntingdon (GB)

(*) Notice: This patent is subject to a terminal disclaimer.

(**) Term: **15 Years**

(21) Appl. No.: **29/832,565**

(22) Filed: **Mar. 29, 2022**

(30) **Foreign Application Priority Data**

Sep. 30, 2021 (GB) 6167309

(51) **LOC (14) Cl.** **07-01**

(52) **U.S. Cl.**

USPC **D7/523**; D7/529

CLAIM

The ornamental design for a cup, as shown and described.

DESCRIPTION

FIG. 1 is a front perspective from below view of a cup according to our new design;

FIG. 2 is a front perspective from above view thereof;

FIG. 3 is a front elevational view thereof;

FIG. 4 is a left-side elevational view thereof;

FIG. 5 is a rear elevational view thereof;

FIG. 6 is a right-side elevational view thereof; and,

FIG. 7 is a top plan view thereof.

The broken lines depict portions of the cup that form no part of the claim.
